(57) **CLAIM**

The ornamental design for a display screen with animated graphical user interface, as shown and described.

DESCRIPTION

FIG. 1 is the first image in a sequence for a display screen with animated graphical user interface showing my new design;

FIG. 2 is the second image thereof;

FIG. 3 is the third image thereof;

FIG. 4 is the fourth image thereof;

FIG. 5 is an enlarged view of the region surrounded by the dot-dash broken line in FIGS. 1-4;

FIG. 6 is the second image thereof;

FIG. 7 is the third image thereof; and,

FIG. 8 is the fourth image thereof.

The appearance of the animated graphical user interface sequentially transitions between the images shown in FIGS. 1-4 and FIGS. 5-8. The process or period in which one image transitions to another forms no part of the claimed design. The broken line showing of the butterflies, the remainder of the user interface and the remainder of the display screen is for environmental purposes only and forms no part of the claimed design. The dot-dash lines define the bounds of the claimed design and form no part thereof.

1 Claim, 8 Drawing Sheets
